UNITED STATES PATENT OFFICE.

RALPH W. CROSBY, OF OSTERVILLE, MASSACHUSETTS.

WRENCH.

1,174,310.

Specification of Letters Patent. Patented Mar. 7, 1916.

Application filed April 13, 1915. Serial No. 21,109.

To all whom it may concern:

Be it known that I, RALPH W. CROSBY, a citizen of the United States, residing at Osterville, in the county of Barnstable and State of Massachusetts, have invented certain new and useful Improvements in Wrenches, of which the following is a specification.

My invention relates to improvements in wrenches and particularly wrenches of the "socket" type.

An object of the invention is to provide for a speedy and easy adjustment of the movable jaw to and from the fixed jaw of the wrench.

A further object of the invention is to provide the coacting jaws, each with a longitudinal and a transverse groove, the grooves, as pointed out hereinafter, permitting each jaw to positively engage two sides of a hexagonal or polygonal nut.

As a further object of the invention I contemplate a wrench structure in which the stresses and strains incident to its use are directly borne by the adjustment means therefor.

I still further contemplate a socket wrench in which the correlated jaws are joined and adjusted in a novel and peculiar manner whereby ease and facility in operation have been perfected to a maximum degree.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:

Figure 1 is a side elevation, partly broken away, of my improved socket wrench; Fig. 2 is an end view; Fig. 3 is a plan view; Fig. 4 is a section on the line 4—4 of Fig. 1; and Fig. 5 is a plan view, a nut having been indicated by dotted lines.

Referring now to the drawings by numerals, 1 designates as an entirety the fixed jaw of the wrench and 2 as an entirety the movable jaw. The fixed jaw 1 in its preferred embodiment may be said to consist of a polygonal shank portion 3, a laterally

grooved connecting portion 4, the groove being designated 5 and the jaw itself designated 6.

The adjustable jaw 2 of the wrench may be said to consist of a body portion 7 provided with a central opening 8 through which the connecting portion 4 of the stationary jaw 1 extends. The jaw proper is designated 9, and is opposed to the mentioned jaw 6, each jaw being longitudinally grooved (V-shaped) to engage with two sides of a hexagonal or polygonal nut as shown to advantage in Fig. 5 of the drawings. The grooves last referred to have been designated 10 in the drawings. The sides of the body portion 7 have been designated 11, said sides being of a dove-tailed formation in cross section whereby to fit complementary grooves 12 therefor formed in the fixed jaw. 75

As a means whereby the dove-tailed sides 11 may be held against vertical displacement I provide retaining blocks 13 of a special size and design, the blocks being located at opposite sides of the fixed jaw 1 and fitting the 80 groove 5 above mentioned, suitable positive fastening means such as indicated at 14 serving to maintain the blocks in place. That portion of the adjustable jaw 2 designated 15, and connecting the sides 11 acts as a 85 stop or abutment to limit movement of the adjustable jaw. A screw 16 penetrates the connecting or abutment portion of the movable jaw 2, the screw being affixed to the connecting portion 4 of the stationary jaw 90 and threadedly engaging the adjustable jaw 2 whereby to move the latter longitudinally of the fixed jaw and relatively thereto through manipulation of the screw. By locating the screw as above pointed out and 95

as shown to advantage in Fig. 1 of the drawings it is apparent that the stresses and strains incident to the use of the wrench are borne directly thereby. Any suitable operating element such as is shown at 17 may 100 be pivotally secured as at 18 to the screw 16 whereby to facilitate manipulation or operation thereof.

In actual practice, the jaws 6 and 9 are first arranged over the nut to be acted on 105 and subsequently adjusted until each jaw is positively engaged with two sides of the nut at diametrically opposite points. When thus adjusted through manipulation of the operating screw 16, it is apparent that a bodily 110 rotation of the wrench as an entirety will loosen or tighten the nut as the occasion may

be. The shank 3 is to be engaged by a wrench or the like tool subsequent to arrangement of the herein described device as above pointed out.

5 From the foregoing, taken in connection with the accompanying drawings it will be noted that the socket wrench herein disclosed comprises but a few simple parts, any or either of which may be replaced with ease 10 should a contingency arise; that undue movement of the correlated wrench parts does not exist, this for the reason that the adjustable jaw is arranged to embrace the fixed jaw, in which position it is fixed 15 against movement other than longitudinal; and that the mode of adjustment here set forth is such in its nature as to receive, as before pointed out, almost the entire strain incident to use or operation of the wrench.

20 Having thus fully described my invention, what I claim as new and desire to secure by Letters Patent, is:—

1. In a wrench, a fixed jaw, a right angle longitudinally grooved body portion integral 25 with said jaw, a reduced shank formed at the opposite end of said body portion, a movable jaw, a right angle body portion integral with the movable jaw, said last mentioned body portion being disposed to overlap and 30 fit the groove in the said first mentioned body portion, said last mentioned body portion having an opening formed therein to receive the shank aforesaid, removable plates carried by said shank to engage with 35 and maintain said last mentioned body portion in engagement with the mentioned grooves, and a means carried by said last

mentioned body portion and engaging with said shank to adjust the movable jaw.

2. In a wrench, a fixed jaw, a body portion integral with said jaw, a reduced shank formed at the opposite end of said body portion, a movable jaw, a body portion integral with said movable jaw, said last mentioned body portion being disposed to overlap and 40 engage with the first mentioned body portion, said last mentioned body portion having an opening formed therein through which the shank aforesaid extends, and a means carried by the shank to engage with 45 the last mentioned body portion to maintain said body portion in engagement with the first mentioned body portion, and means to adjust the movable jaw.

3. In a wrench, a fixed jaw, a body portion integral with said jaw, a reduced shank formed at one end of said body portion, a movable jaw, a body portion integral with said movable jaw, said last mentioned body portion having an opening formed therein 55 to receive said shank, plates carried by said shank to engage with and maintain said last mentioned body portion in engagement with the body portion first mentioned, and a means carried by said last mentioned body portion and engaging said shank to adjust 60 the movable jaw.

In testimony whereof I affix my signature in presence of two witnesses.

RALPH W. CROSBY.
